DESIGN FOR A COMBINED ASH TRAY AND INCENSE BURNER

Conrad E. Meinecke, Buffalo, N. Y.

Application February 26, 1945, Serial No. 118,144

Term of patent 7 years

(Cl. D85—2)

To all whom it may concern:

Be it known that I, Conrad E. Meinecke, a citizen of the United States, residing at Buffalo, in the county of Erie and State of New York, have invented a new, original, and ornamental Design for a Combined Ash Tray and Incense Burner, of which the following is a specification, reference being had to the accompanying drawing, forming a part thereof.

In the drawing:

Fig. 1 shows a perspective view of my design

showing the chimney of the fireplace and the removable ash tray in position of use.

Fig. 2 shows a similar view with the ash tray removed from the fireplace.

Fig. 3 is a fragmentary sectional view taken on line III—III of Fig. 1.

I claim:

The ornamental design for a combined ash tray and incense burner, as shown.

CONRAD E. MEINECKE.
